UNITED STATES PATENT OFFICE.

JESSEE MILTON THOMAS, OF TAMPA, FLORIDA.

BRACING STRUCTURE FOR FOLDING BEDS.

Original application filed March 17, 1924, Serial No. 699,928. Divided and this application filed February 18, 1925. Serial No. 10,132.

To all whom it may concern:

Be it known that I, JESSEE M. THOMAS, a citizen of the United States, and a resident of Tampa, in the county of Hillsborough and State of Florida, have invented certain new and useful Improvements in Bracing Structures for Folding Beds, of which the following is a specification.

10 My invention relates to improvements in bracing structures for the meeting ends of sections of the frame of a folding bed or like frame, and it consists in the combinations, constructions and arrangements 15 herein described and claimed.

The present application is a division of my application for patent for improvement in folding beds, filed March 17, 1924, Serial #699,926.

20 An object of the present invention is the provision of a light but at the same time, strong and durable bracing structure for the meeting end portions of the sections of the frame of a folding bed or like device, the 25 bracing structure affording facilities for positively preventing collapse of the frame at the meeting ends thereof when the frame is extended and for bracing the meeting end portions of the sections of the frames without preventing or interfering with folding 30 of the frame when desired.

Other objects and advantages of the invention will be apparent from the following description, considered in conjunction with 35 the accompanying drawings, in which:

Figure 1 is a side elevation of a folding bed equipped with a practical embodiment of the invention,

Figure 2 is a fragmentary plan view of 40 meeting ends of side rails of the frame and of the adjacent elements of the bracing structure,

Figure 3 is a fragmentary perspective view, showing the structure exhibited in 45 Figure 2 with an end portion of one of the side rails broken away and the position thereof indicated by dash and dot lines, and

Figure 4 is an end view of the bed frame 50 exhibited in Figure 1, with the supporting members at the ends of the bed frame omitted.

In Figure 1, I show a bed frame comprising two cooperative sections 1 and 2 respectively, the section 1 being pivotally attached adjacent to its inner end, as at 3 to

a support 4 and being swingable upwardly and inwardly about a horizontal axis from horizontal position as shown in Figure 1 to the position close to the support 4. The section 2 is provided at its outer end with a 60 supporting structure, such as that indicated generally at 5 which may be of any suitable known construction adapted to support the outer end portion of the section 2 on a flat supporting surface, as at 6 so that the section 2 will be substantially horizontal and will lie in the plane of the section 1 when the latter is horizontal.

Each of the sections 1 and 2 is shown as having side rails. The meeting ends of 70 corresponding side rails of the two sections are provided with lapped portions attached to each other by a horizontal pivot element, as at 7, the two pivot elements 7 being axially alined and lying in an axis which is 75 transverse to the length of the bed frame.

The meeting ends of the sections 1 and 2 are braced against collapse from horizontal position when the frame is extended as shown in Figure 1 by a bracing structure 80 embodying the invention and including a truss-like member indicated generally at 8. This truss-like member 8 is formed of a single tubular member bent to provide a substantially U-shaped body portion 8^a and a portion 8^b for reinforcing the body portion and for staying the arms of the body portion to the web of the body portion. The reinforcing or staying portion 8^b overlies the body portion 8^a and has the intermediate portion thereof secured to the web of the body portion 8^a by a plurality of spaced rivets 9. The reinforcing or staying member 8^b then curves diagonally between the web of the body portion 8^a and the ends 90 of the latter, being merged integrally at one end into the end of one arm of the U-shaped body portion 8^a and being secured at its other end by welding or in any other suitable known manner to the end of the second 95 arm of the U-shaped body portion. The connected together end portions of the U-shaped body 8^a and of the reinforcing staying element 8^b are flattened as indicated at 8^c.

The portion 8^b effectively braces and stays the arms of the U-shaped body portion 8^a to the web of said body portion and tends to hold the latter substantially rigid.

Angular bracing members 10 and 11 re-

spectively are associated with each arm of the **U**-shaped body portion 8^a. One arm of each of the angular bracing members 10 and 11 is relatively long, while the other arm is 5 shorter. The relatively long arm of the bracing member 10 is attached by a horizontal pivot element 12 to the adjacent side rail of one of the frame sections 1 or 2, as to the frame section 1 as illustrated in Figure 1, at a short distance from the inner end of the side rail. The relatively long arm of the other bracing member 11, is attached by a horizontal pivot element 13 to the corresponding side rail of the other bed frame 10 section at the same distance from the inner end of the second bed frame section as the pivot element 12 is located from the inner end of the first bed frame section. The 15 relatively long arms of the bracing members 10 and 11 are equal in length and are pivotally connected to each other at the juncture of the relatively long and the shorter arms of the bracing members 10 and 11 by a horizontal pivot element 14 which is parallel to the pivot elements 12 and 13 and which also connects the members 10 and 11 to the adjacent arm of the substantially **U**-shaped body portion 8^a of the aforesaid truss. The relatively long 20 arms of the members 10 and 11 therefore may be termed rigid links which cooperate with the pivot elements 14 and 13 to connect the **U**-shaped body portion 8^a of the truss to the sections of the bed frame. The 25 relatively short arms of each pair of members 10 and 11 may be considered rigid angular extensions at the inner ends of the pair of members 10 and 11 for a purpose which will be hereinafter stated.

30 With this arrangement, the axes of the two pivot elements 14 will be alined with each other and will lie in a vertical plane in which the axes of the alined pivot elements 7 are disposed. The shorter arms of the 35 bracing members 10 and 11 depend below the level of the pivotal connection at 14 and have notches, as at 15 and 16 respectively for engaging with opposite sides of a horizontal stud projection 17 when the bed 40 frame has been extended so that the sections 1 and 2 lie in the same horizontal plane, as illustrated in Figure 1, the stud projection 17 for each pair of members 10 and 11 being carried by the adjacent arm of the **U**-shaped body portion 8^a of the truss 45 at a lower level than the adjacent pivot element 14 and in the same vertical plane as the corresponding pivot elements 14 and 7.

50 It is to be noted at this point that the position of the pivot elements 14 on the arms of the **U**-shaped body portion of the truss and the length of the members 10 and 11 are such that the joined together ends of the arms of the **U**-shaped body portion 8^a and the staying portion 8^b of the truss will 55 bear against the under faces of the meeting end portions of the side rails of the alined bed frame sections 1 and 2 when the bed frame sections are in horizontal position, and the walls of the notches 15 and 16 of each pair of members 10 and 11 are in contact with opposite sides of the associated stud projection 17. Each stud projection 17 may be termed a stop which cooperates with the associated bracing members 10 and 11 to limit the relative swinging movement of the sections 1 and 2 in one direction about the pivot elements 7 so that collapse of the meeting ends of the sections 1 and 2 from the position illustrated in Figure 1 is prevented. At the same time, the outer ends of the sections 1 and 2 may be swung upwardly and toward each other to cause folding of the bed frame without such folding being retarded by the members 10 and 11 and the stops 17 on the truss. In the case of the particular frame exhibited in Figure 1, the outer end of the section 1 is attached to a stationary support and therefore folding of the bed frame will be effected by swinging the outer end of the section 2 upwardly and then downwardly upon the section 1. However, it is obvious that the improved bracing structure is applicable to hinged together sections of frames other than the particular frame which is illustrated in Figure 1, without departing from the spirit and scope of the invention. Also it is manifest that the particular bracing structure which is illustrated in the drawings and which has been described in the foregoing may be modified and changed in immaterial details without departing from the spirit and scope of the invention, and I therefore consider as my own all such modifications and adaptations thereof as fairly fall within the scope of the appended claims.

60 I claim:—

1. A bracing structure for a frame having a pair of sections pivotally connected together to swing to and from position to lie in the same horizontal plane, said bracing structure comprising a truss-like supporting member having a substantially **U**-shaped body portion and a portion bracing the **U**-shaped body portion, and cooperative elements carried by said **U**-shaped body portion of the truss-like member and the adjacent ends of the bed frame sections for acting conjointly with the truss-like member and the sections of the bed frame to hold said bed frame against collapse when the sections are horizontally alined, said body portion and said bracing portion of the truss-like member being integral portions of a single tubular member, the bracing portion being secured intermediate its length upon the web of the **U**-shaped body portion and having connection at its ends with the ends of the **U**-shaped body portion.

2. A bracing structure for a frame having a pair of sections pivotally connected together to swing to and from position to lie in the same horizontal plane, said bracing structure comprising a truss-like supporting member having a substantially U-shaped body portion and a portion bracing the U-shaped body portion, and cooperative elements carried by said U-shaped body portion of the truss-like member and the adjacent ends of the bed frame sections for acting conjointly with the truss-like member and the sections of the bed frame to hold the said bed frame against collapse when the sections are horizontally alined, said body portion and said bracing portion of the truss-like member being integral portions of a single tubular member, the bracing portion being secured intermediate its length upon the web of the U-shaped body portion and having connection at its ends with the ends of the U-shaped body portion, the connected together end portions of the U-shaped body and bracing portion being flattened.

25 3. In a device of the character described, a truss-like supporting member formed of a single tubular member bent to provide a substantially U-shaped body portion and a portion bracing the U-shaped body portion, the bracing portion being secured intermediate its length to the web of the U-shaped body portion and being integrally joined at one of its ends to an end of the U-shaped body and rigidly secured at its other end to the second end of the U-shaped body, the joined together end portions of said U-shaped body and said bracing portion being flattened.

40 4. In a device of the character described, a truss-like supporting member formed of a single tubular member bent to provide a substantially U-shaped body portion and a portion bracing the U-shaped body portion, the bracing portion being secured intermediate its length to the web of the U-shaped body portion and being integrally joined at one of its ends to an end of the U-shaped body and rigidly secured at its other end to the second end of the U-shaped body, the bracing portion being of less length than the

50 U-shaped body portion and being curved

arcuately between its connection with the web of the body portion and its connections with the ends of the body portion.

5. A bracing structure for a frame having a pair of sections pivotally connected together to swing to and from position to lie in the same horizontal plane, said bracing structure comprising a substantially U-shaped member, a pair of angular bracing members for each arm of the U-shaped member, a horizontal pivot element connecting said bracing members to the adjacent arm of said U-shaped member, the joint of pivotal connection of each angular bracing member with the adjacent arm of the U-shaped member being at the junction of the arms of said angular member, said angular members being pivotally attached to the adjacent sides of said sections of the frame, at equal distances from the inner ends of said frame sections, and a stop projection on the adjacent arm of said U-shaped member for engaging with said angular members below the level of the pivotal connection of the angular members with said U-shaped member, as and for the purpose described.

6. A bracing structure for a frame having a pair of sections pivotally connected together to swing to and from position to lie in the same horizontal plane, said bracing structure comprising a substantially U-shaped member, a pair of rigid links, a single horizontal pivot link attaching the adjacent end portions of said links to the adjacent arm of the U-shaped member, means pivotally attaching the outer ends of said links to the sections of said frame, at equal distances from the inner ends of said frame sections so that the upper ends of said U-shaped member will abut the underfaces of the meeting ends of said frame sections when said frame sections are horizontally alined, a stop on said adjacent arm of the U-shaped member at a level lower than said first named pivot element, and rigid extensions extending below the adjacent ends of said links for engaging with said stop when said frame sections are horizontally alined to stay said meeting ends against collapse.

JESSEE MILTON THOMAS.
